UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

WIRELESS ANTENNA SYSTEM.

Application filed December 14, 1920. Serial No. 430,630.

My invention relates to wireless-telegraph transmission systems and more particularly to antenna structures employed in connection with such systems.

5 In its broad aspect, the object of my invention is to provide an improved elevated antenna system, which possesses marked advantages in economy of material and space, as well as ensuring a decrease in station 10 operating expenses by reason of the large decrease effected in the antenna losses.

More specifically, the object of my invention is to provide an antenna system whereby a number of relatively small antennæ 15 may replace the customary long, low, extensive overhead-antenna systems heretofore employed.

Another object of my invention is to so arrange the separate antennæ that a maximum amount of energy may be radiated for 20 a given energy input.

Still another object of my invention is to provide means whereby the antennæ may be energized simultaneously from a common 25 source of energy.

A further object of my invention is to provide means whereby the customary corona and resistance losses in the conductors leading to the antenna may be limited to 30 minimum values.

The present practice in high-power, long-distance transmission systems is to employ an antenna system in which the conductors forming the antenna extend for long distances substantially parallel to the surface 35 of the earth. In systems of this type, energy is usually supplied to the antenna system at a single point.

By reason of the long antenna employed 40 in such systems, the so-called "capacity effect" is very large thereby causing heavy charging currents to traverse the antenna circuit. As is well known, heavy currents cause large resistance losses which, in turn, reduce the effective transmission range of wireless systems.

One method of reducing the resistance losses, which are caused either by charging currents or by power-currents, is to employ

large conductors in the high-frequency circuits of the antenna system. This method has its limitations by reason of the fact that an increase in the size of the conductors in the inductance coil and the so-called "ground-lead" is not advisable beyond certain limits. Furthermore, no provision is made for reducing the long paths traversed by the charging-currents supplying the extreme end of the antenna system.

According to my invention, I reduce the large charging-current losses heretofore incurred in the long, low antenna systems by dividing the antenna system into a number of small antennæ, the several antennæ being grouped around a central point. Each antenna is connected to ground through an inductance coil which may function both as a tuning device and a so-called "power transformer." Provision is also made for simultaneously energizing the several antennæ from a common source of energy.

My invention may best be understood by reference to the accompanying drawing, in which:

Figure 1 is a diagrammatic perspective view of circuits and apparatus embodying the preferred form of my invention.

Fig. 2 is a diagrammatic perspective view illustrating a modification in the arrangement of the antenna system in the transmission system embodying my invention.

Fig. 3 is a diagrammatic perspective view showing a still further modification in the arrangement of the antenna system.

Like numbers are used to designate like parts having similar functions.

In Fig. 1, I have shown a plurality of non-parallel antennæ 1, 2, 3 and 4 supported in a plane substantially parallel with the surface of the earth by means of towers 5, 6, 7 and 8. Each antenna is connected to a ground conductor 9 through a ground-lead 11 which includes therein an inductance coil 12 that may function both as a tuning device and a so-called "power transformer."

The antennæ are energized from a common source of energy, such, for example, as a high-frequency alternator 13. One terminal

nal of the high-frequency alternator 13 is connected to a ground conductor 14. The remaining terminal is connected to each inductance coil 12, through a conductor 15 and conductors 16, 17, 18 and 19, respectively.

The antennæ 1, 2, 3 and 4 are insulated from one another by means of insulators 21, of a type well known in the art.

10 In Fig. 2 the system shown differs from that of Fig. 1 in the number and arrangement of the antennæ. In this modification, the antennæ, which are arranged in the form of a triangle, are supported by three towers, instead of four, as shown in Fig. 1.

The system shown in Fig. 3 differs from that of Fig. 2 in the radial arrangement of the antennæ. Four towers are necessary to support the antennæ in this arrangement.

20 The tuning coils 12 are so disposed with respect to the antenna system that the length of the ground lead 11 is reduced to a minimum.

The energy radiated by the system may 25 be controlled by any means well known to the art, such, for example, by means of a key (not shown) inserted in the field-winding of the high-frequency generator.

Referring to Figs. 1, 2 and 3, upon closing 30 the controlling key, (not shown), energy is radiated from the antennæ circuits in a manner well known to the art.

While I have shown the separate antennæ insulated from one another, the operation 35 of the system is unaffected by connecting together the several antennæ. One advantage in having the several radiating antennæ electrically independent, is that in case of a breakdown in one of the antennæ, 40 that antennæ may be readily disconnected from the antenna system.

Furthermore, while I have shown a tight coupling between the power-circuits, which include the high-frequency generator 13, 45 ground-conductors 9 and 14, power-conductors 15, 16, 17, 18 and 19 and portion 22 of the tuning coils 12, and the antennæ circuits, each of which includes an antenna and a ground lead 11, the operation of the system, as a whole, is unaffected by employing 50 a loose coupling between the two circuits.

By disposing the power-transformers 12 directly beneath the antennæ, I am enabled 55 to distribute energy to the several antennæ at relatively low voltages. The advantage of this system of distribution resides in the fact that the usual corona losses, in the conductors extending from the source of power to the antenna, are reduced to a minimum 60 value. A further advantage of this system of distribution resides in the decrease effected in the matter of insulating costs.

In my invention, I have provided an 65 antenna system comprising a plurality of non-parallel radiating-antennæ grouped about a

central point, together with means for energizing said antennæ from a common source of energy.

The advantages of such a system are many, such, for example as: the reduction 70 effected in the resistance losses usually incurred in the antenna system and the leads connected thereto; the smaller ground area required as compared to that necessary for the long, low type of antenna heretofore employed; the provision of a radiating system in which the phase-displacement of the waves radiated (with respect to each other) by the several antennæ is substantially zero 80 in value; the large decrease in the cost of construction and maintaining the antenna system; the increase in efficiency obtained by feeding the antenna from a common source of supply; and other advantages brought out in foregoing portions of the specification.

While I have shown three embodiments of my invention, it is obvious, to one skilled in the art, that various modifications may be made in the arrangement of the antennæ and the circuits connected therewith, without departing from the spirit and scope of my invention. I desire, therefore, that only such limitations shall be imposed thereon as are indicated in the appended claims.

I claim as my invention:

1. In a wireless signaling system, a plurality of non-parallel adjacently disposed antennæ grouped about a central point, a ground-lead to the mid-point of each antenna, a tuning coil included in each ground lead and connections whereby each tuning coil may function as a power-transformer.

2. In a wireless signaling system, a plurality of radiating antennæ, a plurality of towers for supporting said antennæ, whereby said antennæ are disposed in substantially a rectangular arrangement, a ground-lead circuit for each antenna and including therein an inductance coil, and means for energizing said antennæ from a common source of energy through said inductance coils.

3. In a wireless signaling system, a plurality of radiating antennæ, a ground-lead circuit for each antenna, an inductance coil included in each ground-lead circuit, said inductance coils being separated by a distance greater than approximately half the length of each antenna, the distance between adjacent ends of said antennæ being less than half the length of any of said antennæ, and means for supplying energy to said radiating antennæ from a common source of energy.

4. In a wireless signaling system, a plurality of radiating antennæ, symmetrically disposed about a central point, a ground-lead circuit for each antenna, an inductance coil included in each ground-lead circuit,

said inductance coils being separated from one another by a distance greater than approximately half the length of each antenna, the distance between the several antennæ

5 and said central point being insufficient to produce noticeable phase differences between the radiations therefrom, and a high-frequency generator, one terminal of which is

grounded and the other terminal of which is connected to said plurality of inductance coils whereby said inductance coils may also function as power-transformers. ¹⁰

In testimony whereof, I have hereunto subscribed my name this 7th day of December, 1920.

FRANK CONRAD.
